UNITED STATES PATENT OFFICE.

GEORGE JEFFARDS WARDWELL AND ALBERT LANDON, OF RUTLAND,
VERMONT.

SELF-COUPING CAR-LINK.

SPECIFICATION forming part of Letters Patent No. 379,621, dated March 20, 1888.

Application filed December 12, 1887. Serial No. 257,622. (No model.)

To all whom it may concern:

Be it known that we, GEORGE JEFFARDS WARDWELL and ALBERT LANDON, citizens of the United States, residing at Rutland, in the 5 county of Rutland and State of Vermont, have invented certain new and useful Improvements in Self-Coupling Car-Links; and we do hereby declare the following to be a full, clear, and exact description of the invention, such as will 10 enable others skilled in the art to which it appertains to make and use the same.

In the accompanying drawings, Figure 1 is a plan view of said link, in which the solid end of the same is supposed to be attached by an 15 ordinary link-pin to the buffer-head of a car which is stationary, while the open-limbed end of the link is just being entered by the link-pin in the buffer-head of an adjacent advancing car with which a coupling is to be effected. 20 Fig. 2 is a like view showing the link-pin of an adjacent car as having advanced in the direction of the arrow to about midway of the length of the car-link, the primary or draft latch, shown in Fig. 1 in working position, having 25 been moved aside from such position across the path of the link-pin to its position outside of said path, as in Fig. 2, during the advancing movement of said link-pin. Fig. 3 is a like view showing said link-pin as having entered 30 the coupling-link to its fullest extent, while Fig. 4 is a central vertical longitudinal section of our self-coupling car-link with the coupling fully effected with an adjacent car, the coupling link-pin being shown in coupled position 35 in section-lines in Fig. 4, but without section-lines in Fig. 1, this view, Fig. 4, also showing our mode of holding the coupling-link in horizontal position, or nearly so, in order to effect a coupling between cars of the same height, 40 while Fig. 5 is a diagram of the coupling-link, showing the same in a reversed and downwardly-projecting position for effecting a coupling between cars of unequal height.

In the drawings, A indicates our improved 45 self-coupling car-link, through the rear solid end, a, of which is a hole, B, as shown, for the reception of a link-pin, b, by means of which to attach the link to the ordinary buffer-head of a railroad-car. This link A, which, prefera- 50 bly, we make of cast-steel, is constructed with

a central open vertical slot, c, its entire length forward of its rear solid portion, a, thus forming projecting limbs, as A' A², on either side of the central vertical slot, c, and which limbs A' A² at their terminating forward ends, a' a², 55 are solid, while they are each constructed with horizontal slots, as c', between the rear solid portions, a, and forward solid portions, a' a², of the coupling-link.

In the slot c' of the limb A', and fitted there- 60 in so as to easily articulate upon a pivot-pin, e, we provide a draft-latch, D, which, when thrown into action, as shown in Fig. 1, has its forward notched end, d, enter into the horizontal slot c' of the limb A², and with its forward 65 surface, d', abutting against the solid extremity a² of said limb, this being the normal position of the draft-latch D to receive the draft of the cars when coupled. Thus after a coupling is effected the coupling link-pin b² (shown in sec- 70 tion-lines in Fig. 4 and without section-lines in Fig. 1) works directly against said latch D, as shown, and in order that no draft or pull shall fall upon its pivot-pin e the draft-latch D is made with a slotted hole, f, to receive the 75 pin e, on which it is pivoted, the draft or pull under such construction falling entirely upon the forward ends of the horizontal slots c' of the limbs A' A².

In the slot c' of the limb A' we also provide 80 a secondary or setting latch, D', constructed in the form shown, and made to articulate on the pivot-pin e'. This latch, in its lateral "throw" within the slot c' of the limb A', is arrested by having its rear end, g, strike upon a stop-pin, 85 e², of the limb A', while its lateral throw toward the limb A² and within its slot c' is limited by the stop-pin e² of the limb A². It will thus be seen that in the operation of coupling, when the link-pin b² (shown in section-lines in 90 Fig. 1) has entered the coupling-link A and passed on to its position therein, as shown in Fig. 2, the primary or draft latch D will have been forced aside from its position shown in Fig. 1 into its position shown in Fig. 2 within 95 the slot c' of the limb A', thereby causing said latch D to press upon the forward end, g', of the secondary latch D' and force such end aside into the slot c' of limb A', as shown in Fig. 2, while this same act forces the forward end, g, 100

of said latch laterally, out away from the slot c' of the limb A' , into the position shown in said figure, and with its end g entered into the slot c' of the limb A^2 and abutting against the stop-pin e^2 , said stop-pin arresting such further movement. The link-pin b^2 , Fig. 2, continuing to pass on in the direction of its arrow, will strike against the edge surface, h , of the secondary or setting latch D' , and, in its passage 10 over such surface, press the rear end of the setting-latch D' laterally into the slot c' of limb A' until the latch is arrested by the contact of its end g upon the stop-pin e^2 , as shown in Fig. 3, but leaving a portion of said end projecting 15 into the slot c in front of and arresting the further forward movement of the link-pin b^2 , while by this same act the end g' of the latch D' and the draft-latch D will be forced from their positions shown in Fig. 2 into their positions 20 shown in Fig. 3, thereby leaving the draft-latch D , under the action of the setting-latch D' , across the path of travel of the link-pin b^2 , in rear of said link-pin, as shown in Fig. 3, so that, the further forward movement of the link-pin having 25 been arrested by contact between the end g of the latch D' and the limb A^2 , and a back action of the adjoining cars taking place by reason of their bumper-heads coming together, which are to be coupled, the link-pin b^2 , Fig. 3, will be forced back against the draft-latch D and both link-pin and latch be made to assume the positions shown by the draft-latch D and the unsectioned link-pin b^2 in Fig. 1, thus 30 fully completing the coupling of the adjoining cars.

It will be seen that the hole B in the solid end $a a a$ of the coupling-link A is beveled, as at m , on the front edge of the hole on one side of the coupling-link, and on the back edge 35 of the hole, as at m' , on the opposite side of

said link, this being done for the purpose of allowing the coupling-link to have a horizontal position, or nearly so, when used one side up, as shown in Fig. 4, while by turning the link over it will have a downward pitch, as shown in Fig. 5, and thus favor its entering the buffer-head of a car which is somewhat lower than one which only can be entered when the link is in horizontal position, as shown in Fig. 4.

It will be seen that our improved car-link is self-coupling; that it can only be uncoupled by the withdrawal of the link-pin b^2 ; that the coupling-latches $D D'$ are simple in form and not subject to undue wear when in action or liable to get out of order, and that our coupling-link can be utilized in connection with most of the buffer-heads of railroad-cars now in use.

What we claim, and desire to secure by Letters Patent, is—

1. The combination, with an open end slotted coupling-link, A , of the horizontal pivoted draft-latch D and the pivoted setting-latch D' , substantially as and for the purpose described.
2. The coupling-link A , provided with a link-pin hole, B , having bevels in reverse relation to each other, substantially as and for the purpose described.
3. The draft-link D , provided with an elongated pivot-hole, f , in combination with limbs $A' A^2$, having horizontal slots c' and solid terminating ends $a' a^2$, substantially as and for the purpose described.

In testimony whereof we affix our signatures in presence of two witnesses.

GEORGE JEFFARDS WARDWELL.
ALBERT LANDON.
